UNITED STATES PATENT OFFICE

96,139

DESIGN FOR A TOY

Karl Schmidt, New York, N. Y.

Application October 5, 1934, Serial No. 53,491

Term of patent 3½ years

To all whom it may concern:

Be it known that I, Karl Schmidt, a citizen of the United States and residing at New York city, in the county of New York and State of New York, have invented a new, original, and ornamental Design for Toys, of which the following is a specification, reference being had to the accompanying drawing, forming part thereof.

I claim:

The ornamental design for a toy, as shown.

KARL SCHMIDT.
